Schenck and forty per cent to said Patterson

Application July 22, 1935, Serial No. 32,594

14 Claims. (Cl. 216—55)

This invention relates to a labeling machine and more especially to a labeling machine where a single label such as a rider has to be applied to both sides of an article and fastened thereto by suitable means such as adhesive, glue and the like. Heretofore, in applying a label or rider ticket to a pair of stockings, it has been necessary for one person to assemble the stockings in pairs and stack them in position for other persons to manually apply the labels thereto. When applying the labels it was necessary for a person to take a single label and apply a suitable moistening means thereto and then to fold the label approximately at its central point so that the moistened adhesive portion would engage opposite sides of the stockings to hold them together. This method is slow and does not produce uniform results since the human element enters therewith and it is only natural that all of the labels would not be applied in the same manner.

It is, therefore, an object of this invention to provide a labeling machine having a plurality of labels therein with means for engaging one label at a time and moistening the same, means for folding the label upon itself and causing the moistened adhesive portion thereof to engage the opposite sides of the stockings and another means for engaging said stockings after the label has been applied to remove it from the point where the label was applied to a suitable conveyor belt.

By providing a machine of this type, it is possible for one employee to assemble and fold the stockings in pairs and at the same time, place them in the machine for labeling purposes. This not only eliminates the necessity of extra help and employment, but the amount of stockings labeled is greatly increased, and also the quality of work done is of a more uniform standard than if done by hand.

It is a further object of this invention to provide in a labeling machine, a self-contained unit comprising a motor, a vacuum means driven by said motor, a magazine containing a plurality of labels which are adapted to be removed one at a time by said vacuum means, and means for applying one of said labels at a time to a pair of stockings, together with means for varying the speed between said motor and said label applying means.

Some of the objects of the invention having been stated, other objects will appear as the description proceeds, when taken in connection with the accompanying drawings, in which:—

Figure 1 is a top plan view of the labeling machine;

Figure 2 is front elevation of Figure 1;
Figure 3 is an elevation of the upper left-hand corner of Figure 1; looking along line 3—3.

Figure 4 is a sectional view taken along the line 4—4 in Figure 2; 5

Figure 5 is a vertical sectional view taken along the line 5—5 in Figure 4;

Figure 6 is a vertical sectional view taken along the line 6—6 in Figure 4;

Figure 7 is a vertical sectional view taken along the line 7—7 in Figure 4;

Figure 8 is a vertical sectional view taken along the line 8—8 in Figure 3;

Figure 9 is a vertical sectional view taken along line 9—9 in Figure 8, but showing the means for 15 engaging a label in the magazine in a lowered position;

Figure 10 is a view showing the label clamping means after it has clamped the label;

Figure 11 is a plan view of the upper central 20 portion of Figure 1 showing the label applying means in operation.

Figure 12 is a view similar to Figure 11 but showing the stocking after the label has been applied and the removing means engaging the 25 stocking for removing the same to a suitable conveyor belt.

Figure 13 is an isometric view of the upper central portion of Figure 1 showing the clamping means in opened position for clamping the 30 stockings after it has been laid upon the labeling machine;

Figure 14 is an isometric view looking at the opposite side of the stocking clamping means while in opened position; 35

Figure 15 is a cross-sectional view taken along the line 15—15 in Figure 1, but showing the removing means moved to its extreme right-hand position where it has engaged a pair of stockings for removing the same; 40

Figure 16 is a view similar to Figure 15 but showing the removing means just prior to its release of a pair of labeled stockings;

Figure 17 is an isometric view showing the removing means in extreme left-hand position 45 with the same being opened;

Figure 18 is a sectional detail view taken along the line 18—18 in Figure 11;

Figure 19 is a view taken along line 19—19 in Figure 3;

Figure 20 is a sectional detail view taken along line 20—20 in Figure 19; 50

Figure 21 is a view showing one end of a plurality of labeling machines positioned in such a manner that the stockings labeled thereby will 55

be collected by a common conveyor belt and conveyed to a common source for packaging.

Referring more specifically to the drawings, the numerals 10, 11, and 12 of Figure 21, indicate labeling machines which are all identical and are shown in detail in the accompanying drawings. The machine 10 has secured thereto a bracket 13 whereas, the machine 12 has a similar bracket 14, both of said brackets having rollers 15 and 16 respectively, rotatably mounted therein with conveyor belt 17 mounted on said rollers for receiving the stockings which have been labeled by the machines 10, 11 and 12 and conducted to this belt. The roller 16 is mounted on a suitable shaft 18 which has fixedly secured on one end thereof a pulley 19. This pulley 19 is driven by any suitable means not shown, and as it turns the conveyor belt 17 conveys the stocking to a common point. This belt may be as long as desired to accommodate machines but in Figure 21 only three machines have been shown to illustrate the principle.

In the drawings, the numeral 20 will be used to designate all portions of the framework of the labeling machine upon which the structure is mounted. Motor 21 is secured to framework 20 (Figs. 2 and 4) and this motor has a pulley 22 upon which is mounted a belt 23, said belt 23 being also mounted on a larger pulley 24 which is rotatably mounted on stud shaft 25. Pulley 24 has integral therewith a small pulley 26 which has a belt 27 mounted thereon. This belt 27 is also mounted upon a variable speed pulley comprising a fixed member 28 and a movable member 29 both of said members being mounted on stud shaft 30.

Member 29 is normally pressed against fixed member 28 by means of a compression spring 31 which has one end abutting the side of member 29 and its other end confined on the shaft 30 by means of a washer 32. A tightening pulley 35 normally rests on the top of belt 27, and this pulley is rotatably mounted on one end of lever 36 which is pivotally secured as at 37 to bracket 38. This bracket is secured to framework 20 and has a plurality of notches cut therein forming a rack, said notches being adapted to be engaged by a suitable dog 39 which is pivoted as at 40 to the lever 36. A spring 41 is provided to normally hold the dog 39 in engagement with the teeth of member 38.

By referring to Figure 2 it is seen that by rotating the lever 36 in a counter-clockwise manner that additional pressure is applied to the belt 27 through pulley 35; therefore, the belt 27 will be caused to travel on a smaller circumference in the variable speed pulley which consists of members 28 and 29 thereby reducing the speed of shaft 30 with respect to the speed of the motor 21. The shaft 30 is rotatably mounted in bracket 45 which in turn is secured to framework 20. This shaft also has fixedly secured thereon a gear 46 which meshes with larger gear 47 mounted on main drive shaft 48 which shaft is rotatably mounted in bearings 49 and 50 secured to framework 20.

The structure thus far described merely shows a driving means for shaft 48 with the proper reduction in gears and means for varying the speed between the motor 21 and shaft 48.

A bracket 55 is secured to the upper portion of framework 20, (Figures 3, 8 and 9), and this bracket has a laterally extending portion upon which is secured a magazine 56 for confining a plurality of labels 57 therein. A Z-shaped por-

tion 58 is secured to the magazine 56, said member 58 having a projection 58a which normally prevents the labels 57 from being pushed out of the magazine. These labels are normally held in the position shown in Figure 9 by means of a suitable plate 60 which is secured on the end of rod 61. The rod 61 is slidably mounted in a collar 62 which is secured on the lower side of magazine 56. The lower side of rod 61 has fixedly secured thereon a bar 63 to which is secured 10 cords 64 and 65, said cords being mounted upon pulleys 66 and 67 respectively, and having weights 68 and 69 secured on the lower end thereof. The pulleys 66 and 67 are fixedly mounted on rod 70 which, in turn, is rotatably mounted in brackets 15 71 and 72 secured to a bracket 55. The weights 68 and 69 normally force the plate 60 into engagement with the stacks of labels 57 and causes the lower end of this stack to be intermittently forced against the projection 58a whereas the upper end of the stack, Figure 9, is intermittently forced against the vacuum means 75 which applies suction to the top-most label and bends one end of it to the position shown in the Figure 9 which will allow the end of the label to be engaged by the clamping means which will be presently described.

Vacuum means 75 is fixedly secured on the end of shaft 76, said shaft 76 being rotatably mounted in bearing 77 which is secured in bracket 55 (see Figure 8). Fixedly secured on the shaft 76 is a lever 78 which projects outwardly and upwardly and has secured to the free end thereof a downwardly extending link 79, the lower end of said link 79 having a slot 79a therein which is penetrated by a shoulder screw 80. (Figs. 3 and 7). This screw 80 is threadably embedded in the free end of another lever 81 pivoted as at 82 to bracket 83. The slot 79a allows a certain amount of play so that the vacuum means 75 will remain in the position shown in Figure 9 for a short period after the lever 81 has been allowed to be lowered by the cam 85 which is fixedly mounted on main drive shaft 48 and which also actuates lever 81, (see Fig. 7).

In order to hold lever 81 into engagement with cam 85 at all times, a tension spring 86 is provided having one end thereof secured to the free end of lever 81 and its other end secured to framework 20. Each time the main drive shaft 48 makes a revolution the high side of cam 85 will raise the lever 81 and rotate the lever 78 to the position shown in Figure 9 thereby causing a label 57 to be placed in position where the clamping means can engage the same.

The vacuum means 75 has a hose 87 secured thereto which leads to a suitable port 88 in cylinder 89. The cylinder 89 is secured to a bracket 90 which, in turn, is mounted upon framework 20 and this cylinder has a piston 91 mounted 60 therein for reciprocatory movement. In Figure 6 the right-hand end of piston 91 is shown engaging the lower side of a cam 92 mounted on main drive shaft 48. Piston 91 has a spring 93 mounted thereon, one end of said spring being adapted 65 to abut against bracket 90 and the other end abutting against a suitable collar 94 fixedly mounted on said piston. This spring normally pushes the end of piston 91 into engagement with cam 92. The piston 91 has a restricted portion 70 91a which fits inside of the cylinder 89 and allows a communication between ports 88 and 96 when in the position shown in Figure 6. When the high side of cam 92 is disposed opposite the right-hand end of piston 91, the piston 91 will 75

be moved to the left and consequently, the port 88 will be closed. The port 96 has a pipe 97 connected thereto, and the other end of this pipe is connected to a compressor 98 which constantly 5 sucks air through vacuum means 75, hose 87, port 88, port 96, and pipe 97, thereby causing a vacuum to be formed in the vacuum means 75. This compressor 98 has a sprocket 99 upon which is mounted a chain 100. Chain 100 is also mounted 10 upon another sprocket 101 fixedly mounted on main drive shaft 48.

In order to cause a label to be bent in the position shown in Figure 9, it is necessary for a vacuum to be formed in vacuum means 75 to cause 15 the upper end of the sheet to adhere thereto.

Immediately after the vacuum has been formed, the high side of cam 85 (Fig. 7), rides beneath the lever 81 and causes the lever 78 (Figures 8 and 9) to oscillate in a clockwise manner, 20 which, in turn will oscillate the vacuum means 75 and bend the label into the position shown. After this is done, the clamping means is lowered first to the position shown in Figure 9, and then to the position shown in Figure 10, where it 25 clamps the upper end of the label.

After the label has been clamped, the vacuum must be released, therefore, at this time the high side of cam 92 in Figure 6 will engage the end of piston 91 to cause the port 88 to be closed. When 30 this is done, of course the vacuum will be broken and no resistance will be offered by member 75 to the label as it is being moved up by the clamping means.

This clamping means comprises a fixed jaw 105 having a pivoted jaw 106 pivotally secured thereto at 107. Leaf spring 108 normally engages the loose pivoted jaw 106 and tends to force the lower end thereof into engagement with the fixed jaw. The pivoted jaw 106 has a projection 106a secured 35 thereto which penetrates the fixed member 105.

It is seen (Fig. 9) that the projection 106a is beveled and is adapted to contact the leaf 109 which is pivoted as at 110 to a bracket 111. This bracket 111 limits the downward movement of 40 leaf 109 and when the projection 106a contacts this leaf on its downward movement, the pivoted member 106 is caused to assume an opened position as shown in Figure 9. This will cause the upper end of the label to occupy a position between the fixed member 105 and the pivoted member 106, and upon further downward movement the projection 106a will move beneath the leaf 109 thereby allowing the member 106 to be closed to the position shown in Figure 10.

55 After the label has been clamped, the clamping means will again start its upward movement to draw the topmost label from the stack of labels. Upon the upward movement, the leaf 109 will assume the dotted line position in Figure 9 to 50 allow the projection 106a to pass therebeneath.

This clamping means is secured to an inverted U-shaped member 112 which projects upwardly, laterally, and then downwardly and is slidably mounted in suitable bearings 113 and 114 which, in turn, are secured to framework 20 and bracket 115 respectively said bracket being also secured to framework 20.

Pivottally secured to member 112 as at 116, 70 (Figure 3), is a downwardly extending link 117 which has its lower end pivotally secured as at 119 to an arm 120. This arm 120 is adjustably mounted on a disk 121 by suitable means such as a set screw 122 which penetrates slot 120a and is 75 threadably secured in disk 120. This provides

means for adjusting the vertical movement or throw of U-shaped member 112.

Each time the drive shaft makes a complete revolution, it is evident that the U-shaped member with the clamping means thereon will likewise make an oscillation or an up and down movement, during which oscillation the label will be clamped and raised to the label applying position. 5

The lower end of bracket 115 has extending 10 therefrom another bracket 123 in which is slidably mounted the upper end of link 124. The lower end of link 124 is pivoted as at 125 to a horizontally disposed lever 126 and the other end of lever 126 is pivoted as at 82 to bracket 83. A 15 spring 127 has one end thereof secured to the free end of link 126 and its other end is secured to framework 20 for normally holding the lever 126 in contact with the cam 128 at all times. This cam 128 is fixedly secured on main drive 20 shaft 48.

It has previously been stated that when the vacuum applying means 75 is turned to the position shown in Figure 9 with the vacuum applied thereto, and the clamping means engages the 25 upper end of the label 57 that the vacuum is then relieved by the means shown in Figure 6 in order that no resistance will be offered to the upward movement of the label.

It is also evident that pressure must be relieved 30 from the lower side of the package of labels 57 or else the friction produced by the weights 68 and 69 would be objectionable and would possibly retard the upward movement of the labels; therefore, it is necessary that the pressure applied to 35 the bottom side of the package of labels 57 be relieved after the clamping means has engaged the labels and is pulling the same to the label applying position.

In order to accomplish the above-described re- 40 sult a dog 130 has been provided on the upper end of lever 124 which is adapted to be raised by the cam 128 to engaging position with the teeth of ratchet wheel 131 which is fixedly mounted on shaft 70. 45

As the label clamping means rises from the position shown in Figure 10, the dog 130 will likewise rise and engage the teeth in ratchet wheel 131 thereby causing it to rotate a slight amount in a counter-clockwise manner which, will cause 50 the shaft 61 and plate 60 to move slightly to the left in Figure 9 to relieve the pressure applied to the bottom side of the package of labels 57. With the vacuum entirely cut off and the pressure on the bottom side of the package of the labels re- 55 lieved, then the upward movement of the label can take place without any resistance or obstruction to said label.

When the labels 57 are packed in the magazine, the surface 133 has a suitable dried adhesive 60 thereon which must be moistened before the labels can be applied to the stockings. In order to provide a suitable moistening means a bracket 134 is secured to the framework 20 which extends downwardly and supports a container 135 which 65 has pivotally mounted therein brushes 136 and 137, the lower ends of which rest in a suitable liquid. The upper ends of these brushes normally rest against arcuate surfaces 138 and 139, and the clamping means is adapted to move 70 downwardly between members 136 to 139 inclusive and engage the upper end of a label 57 which is disposed directly beneath the members 134 to 139 inclusive.

As a label is pulled upwardly the surface 133 75

(Fig. 10) is moistened by the brushes 136 and 137 so that the label will adhere to the stocking when applied thereto.

The bar 124 has connected as at 146 a wire 145 which extends upwardly and is slidably mounted in a collar 147 secured to the lower side of framework 20; (see Figures 8, 13 and 14). When member 124 arises to actuate the ratchet wheel 131 to relieve the pressure on the bottom of the package of labels 57, the wire 145 moves upwardly to raise the leaf 148 to the position shown in Figures 13 and 14. This leaf 148 is pivoted as at 149 and its rotative movement is restricted by means of a suitable block 150 which prevents the leaf 148 from rotating past a vertical position or to a position where it will not fall when the wire 145 is lowered.

A fixed leaf 151 is secured to the top of table 152 and when the parts are in the position shown in Figures 13 and 14 the ribbed portion of a pair of stockings 143 are adapted to be laid upon the top of member 152. When this is being done the label 57 is being raised to the position where it will be bent over the stocking in a position shown in Figure 18.

After the ribbed portions of the stockings have been placed on top of member 151 the rod 145 is lowered thereby allowing the pivoted leaf 148 to fall downwardly upon the top of the stockings.

When this takes place the clamping means has been raised to a position where the central portion of the label 57 will be disposed at the same elevation as the clamping means 148 and 151. In this position means must be provided whereby the label will be removed from the clamping means and caused to fold over the ribbed or top portion of the stockings. 143, therefore, with the label in its upper-most position and ready to be folded on opposite sides of the stockings to a position shown in Figure 18, rollers 153 and 154 are moved to the left in Figure 3 or to the right in Figures 11 and 12 to cause the labels to be folded on opposed sides of the top of a pair of stockings, 143. These rollers 153 and 154 are rotatably mounted in the free ends of frames 155 and 156 respectively, said frames being pivoted as at 157 and 158 to sliding bar 159.

Leaf springs 160 and 161 engage frames 155 and 156 respectively to normally press the rollers 153 and 154 into engagement with each other. By referring to Figure 9 it is seen that when these rollers have been allowed to contact each other, the lower edge of neither roller can be forced lower than the position shown because the diaphragms 155a and 156a on the frames 155 and 156, will engage the enlarged head portion 159a on the end of sliding member 159 and prevent any farther clockwise movement of frame 155 about pivot point 157 and will prevent any farther counter-clockwise movement of frame 156 about pivot point 158 (Fig. 9).

This is to insure that the tangent point between the rollers 153 and 154 will remain at the same elevation at all times and when the sliding member 159 is caused to move to the left to cause the label 57 to be applied to the rib portion of the stockings 143 the proper alignment will be insured.

Figure 11 shows a pair of stockings 143 which are folded in a position on the table top 152 and also showing the label applying means moved to its extreme right-hand position. After the label applying means has moved to the position shown in Figure 11, the clamping means will engage the stockings, (Fig. 12) which have the label applied

thereon and affix the end portions of the label to the stockings and remove the labeled pair of stockings to a conveyor belt so that another pair of stockings may be placed in position for a repeated operation.

In order to cause this label applying means to oscillate back and forth a suitable cam 166 is fixedly secured on main drive shaft 48 and is adapted to be contacted by a roller 167 mounted in the end of rod 168. This rod 168 is slidably mounted in a bracket 169 which, in turn, is secured to framework 20. The other end of rod 168 has secured thereto a vertically disposed lever 170 which has a slot 170a in the lower end thereof which is penetrated by bolt 168a.

The roller 167 is held in contact with cam 166 at all times by a tension spring 172 which has one end thereof secured to the bracket 169 and its other end secured to the end of bolt 168a.

The lever 170 is pivoted intermediate its ends at 171 and also is pivoted at the upper end thereof as at 174 to sliding member 159, said sliding member being slidably mounted in brackets 175 and 176 mounted on the top of framework 20.

For each revolution of the main drive shaft, 25 the label applying means is caused to make one complete oscillation, that is, to move first, to the position shown in Figure 11, and then back again to the position shown in Figure 12, to press and fold the label 57 on opposed sides of a pair of 30 stockings, 143.

By referring to Figure 13 it is seen that table top 152 has a notch 152a cut therein beneath which is a plate 177. This plate is provided to support the pair of stockings immediately after 35 they have been laid upon the table top 152 prior to the applying of the label. Should this plate 177 remain in this position, the rollers 153 and 154 would have to engage the lower side of the plate 177 and the top side of the pair of stockings 40 143 thereby causing the label to be applied to the top of the pair of stockings and to the bottom of the plate 177. To prevent this from taking place means are provided whereby the plate 177 will move to the right in Figure 13 as the label 45 applying means moves to the right to fold the label over the stockings. This means for causing the plate 177 to move to the right consists of a bar 180 which is pivotally secured as at 177a to the bottom of plate 177. (See Figures 1, 15, 50 and 16.)

The other end of this bar is pivoted as at 181 to the upper end of lever 170 (Figs. 1 and 3). It is therefore seen that as the upper end of lever 170 moves to the left in Figure 3, that the plate 55 177 will likewise move which will cause the plate to be removed from the lower side of the ribbed portion of the stockings and allow the label to be applied directly to the lower portion as well as the top portion of stockings 143. It is also necessary 60 for this plate to be moved to the right and out of the notch 152a in order that the means for clamping the labeled pair of stockings may enter and engage the upper and lower sides of said stockings to remove them from the position shown in 65 Figures 11 and 12.

The means for clamping the labeled stockings and removing them from the table top 152 is clearly shown in Figure 17 and comprises a pair of U-shaped brackets 183 and 184 which are secured to the top of framework 20. The structure mounted in each of these brackets is identical in all respects except being opposite hand and a description of the structure shown in member 183 will be given and for member 184 the same refer- 75

ence characters will be given with the prime notation added.

Slidably mounted in the vertical legs of U-shaped member 183 is a bar 185 which has fixedly secured on the right-hand end thereof (Fig. 17) a fixed clamping member 186 and pivoted to the lower side of bar 185 as at 188 is another clamping member 187 which is adapted to cooperate with member 186 when it clamps the opposite sides of a pair of stockings 143 or the like. The pivoted member 187 has a spring 189 normally contacting the lower surface thereof for forcing the member 187 to a closed position.

This spring has one end secured to the lower side of bar 185. An arcuate member 190 is fixed in the pivoted member 187 and projects upwardly through a slot 191 in fixed member 186, the upper end of said arcuate member being adapted to contact the lower side of bar 192 which is slidably mounted in angle bracket 193 secured to the upper side of member 186 and the angle bracket 194 secured to the upper side of member 183. Collars 195 and 196 are secured to the bar 192 to limit its movement during the removal of the stocking from the table top 152. In the position shown in Figure 17, the bars 185 and 192 are shown in their extreme left-hand position and in this position it is seen that the pivoted member 187 is pulled to an opened position.

As the bars 185 and 192 move to the right as shown in Figures 15 and 16, the collar 196 will also move to the right with bar 192 until it engages the angle bracket 194 (Figure 15). At this point the bar 192 will be prevented from moving farther to the right but the bar 185 will continue to move to the right and thereby cause the arcuate member 190 to move out from beneath the end of member 192 and allow the pivoted member 187 to engage the pair of stockings 143 while 187' will engage the label and press label and stockings together. A pin 199 is secured to the end of said bar 192 in order that it will not be impelled to the left far enough to cause the same to be moved out of the bracket 193 when the arcuate member 190 suddenly moves out from beneath the beveled end.

After the bars 185 and 192 have reached the position as shown in Figure 15 and the stockings have been clamped then these members are caused to move to the left in Figure 15. Figure 16 shows the members after they have been partially moved to the left, and just prior to the stockings 143 being released from the clamping means. In this figure collar 195 has moved to the left until it engages bracket 194.

Since it is impossible for the bar 192 to move farther to the left, any farther movement of bar 185 will cause the arcuate member 190 to engage the lower portion of the bar 192 and open the pivoted member 187 to release the pair of stockings which have been labeled. After the pivoted member has been opened the stockings are usually free to fall upon a suitable conveyor belt 200, but in case they should for any reason, remain upon the lower pivoted member 187, suitable guards 201 are provided which will cause the stockings to be pushed off of the clamping means when the bar 185 moves to the position shown in Figure 17.

The conveyor belt 200 is mounted upon rollers 203 and 204, the roller 203 being rotatably mounted in brackets 205 and 206 and the roller 204 being fixedly mounted on shaft 207 which is rotatably mounted in bearings 208 and 209 on the lower side of framework 20.

The bars 185 and 185' are connected to each

other by means of a diaphragm 210 in a manner so that oscillatory motion of one of said bars will cause the same motion of the other.

A cord 211 is secured to one side of a diaphragm 210 and this cord is mounted upon a pulley 212 which is rotatably mounted in the end of bracket 213 as at 214 (Fig. 16). The end of cord 211 is fixedly secured as at 215 to another pulley 216 which is rotatably mounted in bearings 217 and 217a secured to framework 20. Connected to the other side of diaphragm 210 is another cord 218 which is mounted upon a pulley 219 pivoted as at 220 in bracket 221. The other end of this cord is secured as at 222 to wheel 216.

It should be stated here that both of cords 211 and 218 must be anchored to the wheel 216 as well as being mounted thereon so that when the wheel 216 is rotated the bars 185 and 185' will be oscillated. The wheel 216 has integral therewith a pinion 225 which meshes with a larger pinion 226 which is rotatably mounted as at 227 in bearing 228, said bearing 228 being secured to framework 20.

A lever 229 is pivoted as at 230 to pinion 226 and the lower end thereof has a socket secured thereto which is adapted to fit upon a suitable ball 231 on one end of lever 232. This lever is mounted for oscillation as at 233 in a bracket 234 which bracket is mounted on top of framework 20. The other end of bracket 232 has a roller thereon adapted to fit in groove 235 in closed cam 236, which cam is fixedly mounted on main drive shaft 48.

It is seen that rotation of this shaft will cause the lever 232 to oscillate thereby causing the pinion 226 to oscillate first in one direction and then in another. Since the main drive shaft normally rotates in a counter-clockwise manner, the roller on the end of lever 232 is shown in its highest position.

As the cam 236 continues to rotate for this position the roller will be lowered a certain amount thereby causing the point 230 to move upwardly to rotate the pinion 226 in a clockwise manner. This rotation will cause the pinion 225 to rotate in a counter-clockwise manner and cause tension to be applied to cord 211 which, in turn, will pull the members 185 and 185' to the right to a position shown in Figure 15.

With the roller in the position shown in Figure 2 the parts assume the position shown in Figure 1, whereas, when the roller reaches the lower side or its lowermost position, the parts will be in a position shown in Figure 15. When cam 236 continues to rotate from the low side to the high side, then of course the reverse will be true, that is, tension will be applied to the cord 218 and the clamping members will be moved from the extreme right-hand position as shown in Figure 15 to the extreme left-hand position shown in Figure 17. In the meantime of course, point 230 on pinion 226 will move downwardly along with the link 229 and the right-hand end of lever 232. (Fig. 2).

In order to cause the belt 200 to rotate and convey the labeled stockings from the machine a sprocket wheel 241 has been fixedly secured upon the shaft 207 and a sprocket chain 241 mounted thereon. This sprocket chain is also mounted on sprocket 242 (Fig. 4) which sprocket is fixedly secured to main drive shaft 48. As the drive shaft 48 rotates in a counter-clockwise manner the upper portion of the belt 200 will be caused to be moved to the left to convey the stocking from

the machine to another belt 17 which runs at right angles to belt 200.

In the drawings and specification there has been set forth a preferred embodiment of the invention, and although specific terms are employed, they are used in a generic and descriptive sense only, and not for purposes of limitation, the scope of the invention being set forth in the appended claims.

10. We claim:

1. Apparatus for applying rider labels to pairs of stockings comprising means for supporting a pair of stockings in a horizontal position, means for holding a stack of labels, vacuum means for picking a label from the stack, a gripper for seizing the label and moving it into close proximity to one end of the stockings, means for folding the label around the end of the stockings and pressing it to the sides of the stockings, and means for rendering the label adhesive before it is applied to the stockings.

2. Apparatus for applying rider tickets to the ends of pairs of stockings comprising means for supporting a pair of stockings in a horizontal position, means for moving the ticket into position near the end of the stockings, means for rendering the ticket adhesive, and means for folding the ticket over the end of the stockings and applying pressure to the ticket and the stockings to cause the ticket to adhere to the stockings.

3. Apparatus for applying a label to a pair of stockings comprising means for supporting the pair, means for holding a supply of labels, means for moving a label from the supply to a position near one end of the pair of stockings, means for rendering one side of the label adhesive, and means for folding a label over the end of the pair and affixing the label over the end of said pair of stockings.

4. Apparatus for applying a label over the upper end of a pair of stockings comprising means for supporting the pair, means for guarding the end of the pair against dislocation from its position on the support, means for folding an adhesive label over the guarding means and the end of the pair, and means for moving the labeled pair laterally so as to remove the label along with the pair from off the guarding means.

5. Apparatus for applying a label to a pair of stockings comprising means for supporting a pair of stockings means for guarding the upper ends of the pair against dislocation and means for folding an adhesive label over the guarding means and the end of said pair.

6. Apparatus for applying a label to the end of a pair of stockings comprising means for supporting the pair, means for moving an adhesive label over the end of said pair, means for applying pressure to the label and stockings to cause the label to adhere to the stockings, a prong extending over the end of the pair being labeled and over which the label is folded, and means for moving the labeled pair of stockings laterally from beneath the prong and to another part of the machine.

7. Apparatus for applying a label to the end of a pair of stockings comprising means for supporting a pair of superposed stockings means for moving an adhesive label to a position where its center portion is disposed near the end of the pair of stockings and means for folding the label over the ends of the stockings and applying pressure thereto to affix it to the pair of stockings.

8. Apparatus for applying a label over the up-

per end of a pair of stockings comprising means for supporting a pair of superposed stockings means for moving a label to a position at right angles to the end of the pair of stockings, means for folding the label over the end of the pair of stockings and applying pressure thereto to affix the label to the outside surface of each stocking of the pair.

9. Apparatus for applying labels to pairs of hosiery comprising means for supporting a pair of hose, means for supporting a stack of labels, means for folding the label around one end of the support for the hose and on opposed sides of the pair of hosiery, means for applying pressure to the label to cause the same to adhere to the pair of hosiery, and means for removing the labeled pair of hosiery to another position in the apparatus.

10. Apparatus for applying labels to the end of a pair of stockings comprising means for supporting a pair of superposed stockings, means for moving a label into a position near the end of said pair, means for rendering the label adhesive, means for folding the label over the end of said pair, a guard around which the label is folded to prevent dislocation of the pair as the label is applied, and means for engaging the labeled pair of stockings and moving the same to another position in the apparatus.

11. Apparatus for applying a label over one end of a pair of stockings to engage opposed sides of the pair comprising a movable support for the pair, a guard for shielding the end of the pair, means for folding an adhesive label over the guard and the end of the pair so that the central portion of the label will engage said guard and the two end portions of the label will engage the outside portions of the pair, means for moving the support, gripping means for engaging the pair and moving the labeled pair away from the position where the label was applied.

12. Apparatus for applying a label to the end of a pair of stockings comprising means for supporting a pair of superposed stockings, for moving an adhesive label to a position where its center portion is disposed near the end of the pair of stockings, means for folding the label over the end of the stockings and means for applying the pressure thereto to affix it to the pair of stockings.

13. Apparatus for applying labels to pairs of stockings comprising means for supporting a pair of superposed stockings, means for holding a batch of labels, means for removing one label at a time from said batch, means for moving the label to a position adjacent one end of the pair, means for folding the label over the end of the pair, a pair of grippers for engaging the label for an appreciable length of time and pressing it against the hosiery to cause it to adhere thereto and then moving the labeled pair to another position in the apparatus.

14. Apparatus for applying a label to a pair of hosiery comprising means for imparting relative movement between label and a pair of hosiery to cause the label to assume a position near one end of the pair, means for rendering the label adhesive, means for folding the ends of the label over the end of the pair to engage the sides of the pair, and means for applying pressure to the label and hosiery to cause the label to adhere to the pair.
